UNITED STATES PATENT OFFICE.

JOSEPH W. BUCKLAND AND ROBERT MCVICAR, OF MONTREAL, QUEBEC, CANADA.

DRIFTING-VALVE FOR LOCOMOTIVES.

1,284,951.

Specification of Letters Patent. Patented Nov. 12, 1918.

Application filed June 14, 1917. Serial No. 174,810.

To all whom it may concern:

Be it known that we, JOSEPH WELLINGTON BUCKLAND and ROBERT MCVICAR, both of the city of Montreal, Province of Quebec, Dominion of Canada, have invented certain new and useful Improvements in Drifting-Valves for Locomotives; and we do hereby declare that the following is a full, clear, and exact description thereof.

10 This invention relates to the class of drifting valves which supply live steam to the locomotive valve chambers and cylinders when the throttle is closed and the engine is in motion.

15 Our invention has for its object to solve this problem by a substantially direct steam connection from the boiler to the main valve chamber, and to adapt an automatic mechanism to minimize the shocks due to its operation.

20 The invention may be said broadly to consist of a unitary differential valve constructed and arranged to have constantly imparted thereto a tendency to remain closed, and, under abnormal conditions, when the locomotive is drifting for instance, to be sensitive to the atmospheric pressure which opens it and in which the atmospheric pressure is augmented by the auxiliary steam in sustaining it in open position. The auxiliary steam tends to minimize the shock at both ends of travel. This phenomenon is due to the fact that the relief steam at the instant it enters the valve casing is deflected

25 upwardly into the annular cavity in the underside of the valve, the effect being that there is a tendency to keep the valve up, and consequently open. The differential valve and the casing are specially constructed to effect communication between the steam duct leading to the main valve chamber and the upper side of the differential valve thus maintaining a uniformity of pressure on the upper side and a small area of the underside of the differential valve with the effect that a drop in pressure in the cylinder and main valve chamber is instantaneously felt on the upper side of the valve.

30 More specifically stated the invention consists of a differential valve and valve casing, of substantially inverted conical axial section and provided with an annular valvular extension near its apex, the inverted base being 45 in sliding engagement with the interior of a cylindrical portion of the casing, while the

portion of the latter surrounding the annular valvular face contains the auxiliary steam port to which the supply pipe from the boiler is connected. This lower end of the casing 60 terminates in a steam passage adapted to be connected directly to the main valve chamber, and having an upstanding vane within which the apex of the differential valve projects. In the preferred embodiment of our invention uniformity of pressure is obtained on the upper side of the differential valve and the portion of the lower side within the annular valvular face by an axial duct through said differential valve 65 70 which has a chambered interior.

For full comprehension, however, of our invention, reference must be had to the accompanying drawings in which similar reference characters indicate the same parts 75 and wherein:

Figure 1 illustrates, partly in elevation and partly in sectional view, a portion of a locomotive with our invention applied thereto;

Fig. 2 is a sectional view of our improved drifting valve taken diametrically through the same in the plane of the auxiliary steam pipe; and

Figs. 3 and 4 are horizontal sectional views taken on lines 3-3 and 4-4 respectively, Fig. 2.

A portion of the boiler barrel is indicated at b, the main valve chamber at d and the engine frame at e.

Our drifting valve may be connected to the main valve chamber at any convenient point on the steam admission side of the valve, the chamber being bored and tapered to have the shank 2 of the casing of our 95 valve screwed therein.

Our differential valve consists of a substantially inverted conoidal member 3 chambered as at 4 and preferably having an opening 5 axially through its apex which is 100 truncated and of nozzle form. Near the apex an annular or cylindrical valvular extension 6 is provided and the inverted base is extended in a short cylindrical part 7; this cylindrical part 7 and the valvular extension 6 being each provided with circumferential grooves for packing rings 8. The annular extension 6 is connected to the nozzle by a web which constitutes with the nozzle and extension the minor face of the differential valve proper.

The casing of our valve is also of inverted

conoidal form terminating at its apex in a tubular part constituting the shank 2, before mentioned, while its base 10 is of cylindrical form and of sufficiently greater depth than the cylindrical part 7 of the valve to permit axial movement of the latter. Between the shank 2 and the cylindrical portion 10 the casing is of increased thickness in a plane transversely to the annular valvular extension of the valve and substantially midway of its depth in its normal or lowermost position, an annular steam port 12 being formed in this part of the casing, and a pipe coupling boss is being cast in the casing in communication with the port 12. The coupling has the steam pipe 16 leading from the boiler, connected thereto. In order to obtain a comparatively even distribution of the auxiliary steam to all portions of the port 12, a bushing 30 is located within the portion of the casing containing the port and it has 3 openings 31, 32 and 33 while the port of the casing is eccentric to the bushing 30 thereby imparting to the part 12 a greater capacity at its intake end and diminishing to the second and third ports 32 and 33.

The casting between the steam port 12 and the inverted base has an opening 20 effecting communication between the atmosphere and a circumferential concave face 21 formed on the exterior of the differential valve.

It will be noted that the diameter of the differential valve extension 6 is considerably less than the diameter of the base 7. This difference of diameters with corresponding pressure on each insures a normal downward position of the valve, and when pressure in the locomotive-cylinder and consequently in the main valve chamber and the pressure 17 through the steam of our valve, drops to pressure less than atmospheric the atmospheric pressure will lift the differential valve and admit steam from the steam pipe 16 direct to passage 17 and the main valve chamber.

A cap 18 closes the top of the casing. The upper end of the tubular shank 2 is projected in the form of a vane 25 and the underside of the valvular extension 6 is recessed to form a chamber 50 which receives this vane with sufficient clearance to have the entire under-surface of the differential valve within the diameter of the valvular extension exposed to the pressure of the auxiliary steam when our valve is raised.

Operation.

60. In the operation of our invention, the engine being in motion, when the throttle is closed and the steam pressure in the main valve chamber and cylinder drops below atmospheric pressure, the differential valve is lifted thus uncovering the port 31, 32 and 33

and admitting auxiliary steam direct to the main engine valve chamber through steam passage 17.

This flow of the steam first exerts a lifting effect on the valve being deflected upwardly 70 by the vane 25 into contact with the minor face of the valve proper. The steam is then deflected downwardly and following the surface of the nozzle is concentrated in a solid jet at a point immediately beneath 75 and in close proximity to the truncated apex of the nozzle thus exerting a suction within the chamber 4 which tends to maintain the lifting forces exerted on this valve when the drop in pressure occurred in the cylinder. 80

The atmospheric pressure and steam pressure acting directly in the lower side of the lifted valve and the suction above mentioned, on the upper side thereof, all maintain the valve in its lifted and open position until 85 the engine comes to a stop or pressure builds up in the cylinder and main valve chamber. The effect is that the high pressure exerted through the opening 5 in the valve on the upper side, lowers it and closes the ports 31, 32 90 and 33 which cuts off the steam. This is the normal position of our valve while the engine is running under steam and it remains in this position until there is another drop in pressure in the cylinder, as above described. 95

When the throttle is opened and the differential valve is in its upward position the sudden rise in pressure on the large diameter of the latter would have a tendency to drive it 100 to its lowermost position with considerable shock. The combined action of the chamber 50 and pocket 26 minimizes this shock in the following manner. The annular pocket 26 surrounding the vane and inclosed by the 105 outer wall of our casing serves to contain some of the high pressure steam from the relief pipe 16 which cushions the fall of our valve and absorbs the shock owing to the fact of the relatively small area of the annular passage between the top of the vane and the contiguous portion of the recessed underside of the valve which creates sufficient friction to retard the final downward movement of the valve. The steam contained in the chamber 4 of our valve and which can escape only by the restricted opening 5, when this valve is lifted by a drop in pressure in the cylinder, in a similar manner cushions the blow on the cap and absorbs the 110 shock. 115

What we claim is as follows:—

1. A valve of the type described comprising a differential valve with truncated apex of nozzle form and an annular valvular extension near its apex and of less diameter than the base of the valve, the minor face of the said differential valve having an annular concavity concentric to and between the said apex and annular valvular extension; a valve 125

casing containing the said differential valve and having a steam supply port controlled by the said annular extension, a steam outlet passage in close proximity to the port and 5 inclosing the apex of the differential valve, and an annular baffle-vane forming the intake end of the outlet passage, the said vane registering with the said annular cavity, and the interior of the opposite end of the casing 10 being of cylindrical form and of sufficient depth to accommodate the differential valve in its operation of opening and closing the steam port, the casing having an opening to the atmosphere at a point at which atmospheric pressure will be exerted upon the exterior of the differential valve for the purpose of actuating the latter when pressure within the same becomes less than atmospheric, and means whereby permanently 15 open communication is effected between the cylindrical portion of the casing and the steam outlet passage.

2. A valve of the type described comprising a differential valve with an annular valvular extension near one end and of less diameter than the opposite end of the valve and having a nozzle in its axial line and a surrounding annular concavity; a valve casing containing the differential valve and 20 having a steam supply port controlled by said valvular member, a steam outlet passage in close proximity to the port and the said interior of the casing having an integral annular baffle-vane forming 25 the inner end of the said steam outlet passage and registering with the said annular concavity, and the interior of the opposite end of the casing being of cylindrical form and of sufficient depth to accommodate 30 the differential valve in its operations of opening and closing the steam port, the casing having an opening to the atmosphere at a point at which atmospheric pressure will be exerted upon the exterior of the 35 differential valve for the purpose of actuating the latter when pressure within the same becomes less than atmospheric, and means whereby permanently 40 open communication is effected between the cylindrical portion of the casing and the steam outlet passage.

3. A valve of the type described comprising a differential valve with an annular valvular extension near the minor end of the valve and having a nozzle projecting from 45 its minor side in its axial line; a valve casing containing the differential valve and having a steam supply port controlled by said valvular member, a steam outlet passage in close proximity to the port and in 50 the axial line of the differential valve, an annular baffle-vane formed integrally with the casing and forming an extension of the passage toward the valve, and the interior of the opposite end of the casing being of 55 cylindrical form and of sufficient depth to

accommodate the differential valve in its operations of opening and closing the steam port, the casing having an opening to the atmosphere at a point at which atmospheric pressure will be exerted upon the exterior of the differential valve for the purpose of actuating the latter when pressure within the same becomes less than atmospheric, and an axial opening through the valve whereby permanently 60 open communication is effected between the cylindrical portion of the casing and the steam supply passage.

4. A valve of the type described comprising a differential valve with an annular valvular extension near one end and of less diameter than the base of the valve and having a nozzle projecting from its minor side in its axial line, the external surface of the valve between the annular valvular member and the base presenting a circumferential concavity; a valve casing containing the differential valve and having a steam supply port controlled by said annular valvular extension, a steam outlet passage in close proximity to the port and in the axial line 70 of the differential valve, an annular baffle vane formed integrally with the casing and forming an extension of the passage toward the valve, and the interior of the opposite end of the casing being of cylindrical form and of sufficient depth to accommodate the differential valve in its operations of opening and closing the steam port, the casing having an opening to the atmosphere coinciding with the concave portion of the valve, 75 and the differential valve having an axial opening therethrough whereby permanently open communication is effected between the cylindrical portion of the casing and the steam outlet passage at a point contiguous to the nozzle.

5. A valve of the type described comprising a differential valve with a valvular member near the end and of minor diameter and having a nozzle projecting from its minor side in its axial line; a valve casing containing the differential valve and having an eccentric steam supply port controlled by said valvular member, and a bushing with a plurality of ports therein communicating with the supply port, a steam outlet passage in close proximity to and in direct communication with the supply port, and the interior of the opposite end of the casing being of cylindrical form and of sufficient depth to accommodate the differential valve in its operation opening and closing the steam port, the casing having an opening to the atmosphere at a point at which atmospheric pressure will be exerted upon the exterior of the differential valve for the purpose of actuating the latter when pressure within the same becomes less than atmospheric, and means whereby a 100 permanently open communication is effected 105

between the cylindrical portion of the casing and the steam outlet passage.

6. In a drifting valve the combination with a valve casing having steam intake and outlet ports in relative right-angular arrangement, an annular vane forming an inward extension of the outlet port and intersecting the steam inlet port, of an automatic differential valve adapted to control the steam inlet port, the minor pressure face of the differential valve having an axially disposed nozzle and a surrounding annular chamber in registering relation with the vane, and means whereby an open communication is effected between the outlet port in the vicinity of the nozzle and the major pressure face of the differential valve.
7. In a drifting valve the combination with a valve casing having steam intake and outlet ports in relative right-angular arrangement, an annular vane forming an in-

ward extension of the outlet port and intersecting the steam inlet port, of an automatic differential valve adapted to control the steam inlet port, the minor pressure face of the differential valve having an axially disposed nozzle and a surrounding annular chamber in registering relation with the vane, and an axial port through the said differential valve and nozzle whereby an open communication is effected between the outlet port in the vicinity of the nozzle and the major pressure face of the differential valve.

In testimony whereof we have signed our names to this specification in the presence of two witnesses.

JOSEPH W. BUCKLAND.
ROBERT McVICAR.
